UNITED STATES PATENT OFFICE.

WILLIAM H. DOBLE, OF QUINCY, MASSACHUSETTS, ASSIGNOR OF ONE-FOURTH TO
PNEUMATIC SCALE CORPORATION, LIMITED, OF QUINCY, MASSACHUSETTS, A
CORPORATION OF MAINE.

HOLLOW PANEL.

1,296,272.

Specification of Letters Patent.

Patented Mar. 4, 1919.

Application filed July 22, 1918. Serial No. 246,239.

To all whom it may concern:

Be it known that I, WILLIAM H. DOBLE, a citizen of the United States, residing at Quincy, county of Norfolk, State of Massachusetts, have invented a certain new and useful Improvement in Hollow Panels, of which the following is a specification, reference being had therein to the accompanying drawings.

- 10 The invention relates to a new and useful improvement in hollow panels composed of two parallel plates forming the respective faces of the panel and an interposed truss plate which is united to the two face plates.
- 15 The invention is intended to be especially applied in the construction of panels for use in making boxes, more particularly that type of boxes in which the panels have hinged connection with each other so that the box
- 20 may be folded or knocked down but the invention is not limited to use in connection with the manufacture of folding boxes or even boxes of any character, the invention being applicable to the construction of hollow panels for any purpose in which strength and lightness are both desired. For convenience of illustration the drawings show the invention as applied to a box panel.

The invention will be fully understood 30 from the following description when taken in connection with the accompanying drawings and the novel features thereof will be pointed out and clearly defined in the claims at the close of this specification.

35 In the drawings, Figure 1 is a plan view of a panel constructed in accordance with the invention.

Fig. 2 is a cross section on line 2—2 of Fig. 1.

40 Fig. 3 is a plan view of a portion of the panel shown in Fig. 1 on an enlarged scale, the panel being partly broken away.

Fig. 4 is a section on line 4—4 of Fig. 3.

45 Fig. 5 is a sectional view taken on a similar line to that on which Fig. 4 is taken showing a modified form of reinforcing or truss plate.

Fig. 6 is a section showing the truss members bent on a sharper angle than in Fig. 4, and the flat faced portions extending across the width of the V-shaped sections.

50 Referring now to the drawings, 1 and 2 represent respectively the two face plates of the panel, being made preferably of thin sheet metal, the two plates being parallel to

each other and preferably having flat surfaces. Interposed between these two face plates is a truss plate 3 which is bent in such form as to have certain portions contacting with the face plate 1 and certain portions 60 contacting with the face plate 2. In the form shown in Figs. 2 and 4 the truss plate is bent or formed to make a succession of angular undulations which are alternately V-shaped and inverted V-shape in cross section, the apexes or ridges of the undulations contacting alternately with the face plates 1 and 2, that is as shown, the apexes 4 of the inverted V-shape portions contact with the upper face plate 1 as viewed in the drawings 70 and the apexes 5 of the V-shaped portions contact with the lower face plate 2.

In cross sectional view as shown in Figs. 2 and 4 the portions which cross from one face plate to the other give together a zig-zag appearance. These transverse portions serve to brace the two face plates and will be referred to as strut portions. Each strut portion is in a plane which is inclined to the faces of the face plates. For convenience of designation the right hand strut portion of each V-shaped section is indicated by the numeral 6 and the left hand strut portion is designated by the numeral 7. The strut portions 6 and 7 thus alternate with 80 each other, the strut portions 6 being all parallel with each other and the strut portions 7 being all parallel with each other.

It is important that these reinforcing or truss members shall be united to the inner 90 and outer face plates so as to retain them firmly in position. If the truss plates were simply secured to the face plates along the lines of the apexes or ridges 4, 5 this would furnish merely a line contact and union 95 which is insufficient to give proper strength and rigidity. It is important that there should be a contact and union of some surface area between the ridges of the truss plates.

100 For reason of economy in construction and for strength it is desirable that these contact surfaces of the truss plate should be integral with the truss plate and to this end there are formed a series of flat faced contact portions 8, 9 struck up out of the strut portions of the truss plates and bent to form contact with the two face plates 1, 2. These struck up portions may be formed by cutting slits so as to form tabs 110

which are united with the truss plate along the lines of the ridges. In order to properly distribute the said contact faces the portions 8 which contact with the upper face plate 1 are struck up out of the strut portions 6 and the contact portions 9 which contact with the lower face plate 2 are struck up out of the strut portions 7. Thus there is a symmetry in the arrangement of 10 the contact portions which engage the two face plates and they are so arranged that the contact faces which engage the upper face plate do not come directly opposite the contact faces which engage the lower face plate. 15 Moreover it will be seen from Fig. 4 that the contact faces extend from the ridge portions out over the throat or mouth of the V-shaped troughs. These flat contact surfaces are made in short sections as will be 20 seen from Fig. 1, and Fig. 3, there being several such portions struck up in the course of the length of each strut portion 6 and 7 with an interval between the struck up portions of each strut so as to avoid weakening 25 too much the strut portions.

Each flat faced contact portion 8, 9 is united firmly to the face plate with which it contacts by any suitable means that makes a permanent firm connection. This union 30 is preferably effected by means of what is known as the sweating process which fuses the two contacting faces together with an interposed fusible metal or forming the plates with a fusible metal facing or it 35 may be done by soldering or even by riveting or other suitable means, but the sweating process is preferable so that when the parts are united it makes the entire panel virtually integral.

40 In the modification shown in Fig. 5 in forming the apexes or ridges 10 they are somewhat curved instead of sharp so that as viewed in end elevation or sectional view the truss plate has an undulating appearance. The flat faced contact portions 8 and 45 9 respectively are struck up in the same manner as already described.

In the modification shown in Fig. 6 the flat faced contact portions 8, 9 extend across 50 the entire width of the mouth of the V and the edges 11 of the said contact portions 8, 9 engage with the strut portions 7, 6, thereby somewhat increasing the rigidity of the structure.

55 What I claim is:

1. A hollow panel composed of two face plates parallel with each other and an interposed truss plate having strut portions which extend crosswise from one face plate 60 to the other, and having tab portions which

form flat faced surfaces which contact with said face plates.

2. A hollow panel composed of two face plates parallel with each other and an interposed truss plate having strut portions which extend crosswise from one face plate to the other, and having tab portions which form flat faced surfaces which contact with said face plates, said flat faced contact portions being firmly united to the said face plates. 65

3. A panel composed of two face plates parallel with and spaced apart from each other and an interposed truss plate having strut portions which extend crosswise from one face plate to the other, said strut portions having tabs struck up therefrom some of which contact with one of said face plates and others of which contact with the other of said face plates. 70

4. A panel composed of two face plates parallel with and spaced apart from each other and an interposed truss plate having strut portions which extend crosswise from one face plate to the other, said strut portions having tabs struck up therefrom some of which contact with one of said face plates and others of which contact with the other of said face plates, said tabs being united to the plates with which they contact 80 throughout the entire contacting surfaces. 85

5. A panel composed of two face plates parallel with and spaced apart from each other and an interposed truss plate shaped to form a series of strut portions which extend crosswise zig-zag from one face plate to the other with ridges at the junction of each pair of adjacent struts which engage with the respective face plates, said strut portions having sections thereof struck up 90 in the form of tabs which form flat faced contacts with said face plates, said truss portions being firmly united to the said face plates in the contacting portions both of the ridges and of the said tabs. 95

6. A hollow panel having an inner and an outer wall plate spaced apart from each other and an interposed truss plate bent to form strut portions which extend crosswise between the two wall plates, the bends in the truss plate between the strut portions forming ridges which alternately contact with the two wall plates and having also flat faced portions which project from the contacting ridge portions some of which contact with one of said wall plates and others of which contact with the other of said wall plates. 100

In testimony whereof I affix my signature.
WILLIAM H. DOBLE.
